UNITED STATES PATENT OFFICE.

EDWARD A. LEE, OF HAILEYBURY, ONTARIO, CANADA.

BOTTLE CLEANER.

1,420,714.

Specification of Letters Patent. Patented June 27, 1922.

Application filed March 3, 1920, Serial No. 362,992. Renewed November 19, 1921. Serial No. 516,519.

To all whom it may concern:

Be it known that I, EDWARD A. LEE, a subject of the King of England, residing at Haileybury, in the Province of Ontario and 5 Dominion of Canada, have invented certain new and useful Improvements in a Bottle Cleaner, of which the following is a specification.

This invention is a bottle cleaner and has 10 for its principal object the production of a device which may readily be inserted within a bottle and then may be actuated to cause the cleaning bars carried thereby to engage the bottle as the cleaner and the bars 15 will move over the inner surface of the bottle and clean the same.

One practical form of construction and assembly of the present invention will be hereinafter described and is illustrated in 20 the accompanying drawing, in which—

Figure 1 is a side elevation of the bottle cleaner illustrating in dotted lines the manner in which the same is used.

Figure 2 is an elevation of the bottle 25 cleaner, taken at right angles to Figure 1, and

Figure 3 is an enlarged fragmentary sectional view of a portion of the device illustrating the manner in which the sleeve is 30 mounted upon the rod.

In the preferred embodiment of the present invention about to be described, it will be seen that 5 indicates the supporting rod which has an eye 6 at its outer end, thus 35 allowing the rod to be carried upon a suitable supporting element, such for instance as a nail when the bottle cleaner is not in use. This rod 5 is provided with a plurality of teeth 7 formed thereon, as illustrated specifically in Figure 3. The rod is provided 40 with eyes 8 at its opposite end, as shown in Figure 1.

The sleeve 9 is movably mounted upon the rod 5 as shown in Figure 3. This sleeve 9 45 has a central bore 10 through which the rod 5 extends and it will also be noted that the sleeve is provided with an enlarged internal pocket 11. The resilient pawl 12 is fixedly secured as shown at 13 to the interior of 50 the sleeve 9 within the pocket 11. The shifting button 14 has a stem 15 provided with a head 16. The stem 15 extends through the slot 17 in the sleeve, whereby the button may 55 be easily moved toward either end of the sleeve 9. Under normal conditions the button is in the position indicated in dotted

lines in Figure 3, thus allowing the sleeve to be freely moved along the rod 5. When however, the button is moved to the position indicated in full lines in Figure 3, it 60 will force the free end of the resilient pawl 12 into engagement with the teeth 7 of the rod 5, thus holding the sleeve against accidental shifting in one direction.

The strands 18 are fixed to the sleeve 9 in 65 any suitable manner and extend contiguous to the rod 5. The links 19 are pivotally connected together, as indicated at 20 and the links 19 are also pivotally mounted upon the end of the strands 18 as shown at 21. The 70 remaining ends of the links are pivotally mounted upon the eyes 8 carried by the rod 5. It is therefore obvious that when the sleeve 9 is shifted toward one end of the rod 5, it will cause the strands 18 to swing the 75 connected ends of the links outwardly to the position indicated in dotted lines in Figure 1, although when the sleeve 9 is moved toward the eye 6, the links will move to collapsed positions, as shown in full lines in 80 Figure 1. The cleaning bars consist of strips 22 of flexible material which have eyes 23 connected to the links 19 at the portions 20, as shown clearly in Figure 1. The felt or other suitable cleaning material cleaning 85 strips 24 are positioned upon the flexible strips 22, thus providing flexible cleaning bars which have strips which will efficiently clean surfaces over which the same are passed.

When the device is in operation, it is first 90 inserted into the bottle as indicated in Figure 1 and then the sleeve 9 is moved away from the end of the bar having the eye 6. This movement will cause the strands to shift the 95 connected ends of the links outwardly as indicated in dotted lines in Figure 1, thus causing the cleaning bars carried by these links to be moved into engagement with the inner surfaces of the bottle in which the same are carried. At this time, the button 14 is shifted to bring the resilient pawl 12 into a binding engagement with one of the teeth 7 of the rod 5, thus holding the sleeve against accidental movement in the opposite 100 direction. The rod may then be reciprocated or turned as desired, and it is obvious that the cleaning bars will be moved over the inner surfaces of the bottle for cleaning the same. It will be noted that these cleaning bars extend beyond the end of the rod 105 and for this reason may be moved into en-

gagement with the bottom of the bottle for cleaning the same, without interference from the rod. Furthermore, it will be noted that the cleaning bars are pivotally supported off-center, thus allowing the bars to have a greater amount of movement when the links are shifted for moving the bars into operative positions. Also since the cleaning bars are of a flexible nature, it is obvious that as the bars are moved onto the curved surfaces of a bottle, they will easily fit snugly upon said curved surfaces for cleaning the same as the cleaner moves.

After the inner surfaces of the bottle have been cleaned by the movement of the cleaner, the button may be returned to its normal position, thus allowing the resilient pawl to move from the binding engagement with the teeth 7. Therefore, the sleeve may be shifted toward the eye 6 thus pulling upon the strands 18, which in turn will pull upon the links to return the same to their normal collapsed positions, as indicated in full lines in Figure 1. This action will also return the cleaning bar to its normal position and for this reason will allow the bottle cleaner to be removed from the bottle.

The foregoing description and the drawings have reference to what may be considered the preferred, or approved, form of my invention. It is to be understood that I may make such changes in construction and arrangement and combination of parts, mate-

rials, dimensions, et cetera, as may prove expedient and fall within the scope of the appended claims.

Having thus fully described my invention, what I claim as new and desire to secure by Letters Patent, is:—

1. A cleaning device of the class described including cleaning elements, a rod, a sleeve thereon, means connecting the cleaning elements to the sleeve, said sleeve provided with an internal pocket, a resilient pawl fixed to the interior of the pocket so as to lie along the interior thereof, teeth on the rod, and means for pushing the pawl in engagement therewith. 40

2. A cleaning device of the class described, including cleaning elements, a rod, a sleeve thereon, means connecting the cleaning elements to the sleeve, said sleeve provided with an internal pocket, a resilient pawl fixed to the interior of the pocket so as to lie along the interior thereof, teeth on the rod, said sleeve provided with a slot, a button having a shank extending through said slot and adapted to push and retain said pawl in engagement with the teeth. 50

55 In testimony whereof I affix my signature in presence of two witnesses.

EDWARD A. LEE.
